(57) CLAIM

The ornamental design for a bottle for dispensing cosmetics, as shown and described.

DESCRIPTION

FIG. 1 is a front perspective view of a bottle for dispensing cosmetics showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken line shown of a collar and nozzle is for illustrative purposes only and forms no part of the claimed design.
